Primary Examiner — Ieisha N Price

CLAIM

The ornamental design for a weed removal tool, as shown and described.

DESCRIPTION

FIG. 1 is a front, left perspective view of the weed removal tool.

FIG. 2 is a rear, right perspective view of the weed removal tool.

FIG. 3 is a front view of the weed removal tool.

FIG. 4 is a rear side view of the weed removal tool.

FIG. 5 is a left side view of the weed removal tool.

FIG. 6 is a right view of the weed removal tool.

FIG. 7 is a top view of the weed removal tool; and,

FIG. 8 is a bottom view of the weed removal tool.

The broken lines showing of the handle renders environmental structure and forms no part of the claimed design.

1 Claim, 8 Drawing Sheets
